WASHINGTON I. HOOPES, JR., OF ARDMORE, PENNSYLVANIA.

TIMED CONTROLLING DEVICE.

1,118,772.

Specification of Letters Patent. Patented Nov. 24, 1914.

Application filed July 8, 1914. Serial No. 849,631.

To all whom it may concern:

Be it known that I, WASHINGTON I. HOOPES, Jr., a citizen of the United States, residing at Ardmore, in the county of Montgomery, State of Pennsylvania, have invented a new and useful Timed Controlling Device, of which the following is a specification.

My invention relates to a new and useful improvement in timed controlling device, and consists of means in suitable connection with an alarm clock for controlling an electric switch or switches, whereby the same will automatically operate.

15 It further consists of means held in operative position and adapted to be released by the alarm mechanism of a clock, for controlling a switch or switches.

15 It further consists of means for controlling the alarm stopping device.

20 It further consists of other novel features of construction, all as will be herein-after fully set forth.

25 For the purpose of illustrating my invention, I have shown in the accompanying drawings one form thereof which is at present preferred by me, since the same will give in practice satisfactory and reliable results, although it is to be understood that 30 the various instrumentalities of which my invention consists can be variously arranged and organized and that my invention is not limited to the precise arrangement and organization of these instrumentalities as 35 herein shown and described.

Figure 1 represents a side elevation of a timed controlling device, showing a clock in suitable location therewith, and one electric switch. Fig. 2 represents a top plan view thereof. Fig. 3 represents a sectional view on line α — α Fig. 2.

Similar numerals of reference indicate corresponding parts in the figures.

Referring to the drawings:—1 designates 45 a base or support of the device, which may be of any suitable form of construction, and which is preferably provided with means for receiving a clock, such as an alarm clock 2, which may be of any suitable or desired 50 construction, and which, as here shown, is provided with an alarm winding switch 3, having a key 4 thereon, and also provided with an alarm stopping member 5, which may be of the manually operated type, but 55 which, as here shown, has connected therewith, a weight, 6, which will tend to lower

the member 5 to its inoperative position, and thus tend to stop the alarm. It will be understood that the type of clock shown is that form, which, when the alarm is sounded, the shaft 3 and key 4 rotate at a comparatively rapid rate. Suitably carried by the support 1, as here shown, are the two standards or supports 7 and 8, each of which is provided with a suitable opening, in which is rotatably and slidably mounted a rod 9, which, in the present instance, is provided with an offset portion 10, forming an abutment, and having an end 11, which, when the rod is moved to operative position, is situated in the path of movement of rotation of the key 4 of the shaft 3, whereby the said rod is adapted to be engaged with said shaft.

12 designates a slot, of suitable extent, 75 formed in the standard 7 and extending laterally therein.

13 designates an electric switch, which is in suitable electrical connection with an electric circuit controlling any number of 80 lights, said switch 13 having the contact points 14 and 15, and the switch arm 16, having a finger-piece 17, which, as here shown, is, in one position, adapted to be in engagement with the end of the rod 9. 85 It will be understood that while I have shown the switch 13 as mounted upon the support 1, the said switch can be situated at any suitable or desired point, it only being necessary that the switch arm 16 thereof 90 is in position to be engaged by the rod 9 and actuated thereby, as will be hereinafter described. It will be further understood that by moving the switch arm 16 from its position in engagement with one contact 95 point to another, it can be made to either switch on or switch off a light or lights, depending upon the use to which the device is to be used.

18 designates a spring in suitable relation 100 to said rod 9, which is adapted to move the rod to its inoperative position, as, for example, in the direction indicated by the arrow in Fig. 1. As here shown, the said spring is of the coiled type, having one end 105 abutting the standard or support 7 and the other end abutting an adjustable stop 19 carried on the rod 9, and said spring being adapted to be compressed when the rod 9 is moved to operative position.

20 designates an arm in suitable connection with the rod 9, as here shown, the said

arm 20 being slidably mounted in the ears 21 carried by the support 1, and said arm 20 being connected with the rod 9 by a bar 22, which, while permitting rotation of the rod 9, moves in conjunction with the rod 9, as will be evident, it being understood that the end of said arm 20, when the rod 9 is moved to operative position, is adapted to pass beneath the alarm stopping member 5 and 10 serve to support the same and hold it in elevated or operative position.

It will be noted that the switch 13 is secured in position by means of a fastening device 23, see Fig. 2, whereby the same may 15 be rotatably adjusted to vary the relative position of the contacts 14 and 15 with respect to the end of the rod 9.

The operation of my novel device will now 20 be readily apparent, and is as follows:—Assuming that the alarm has been wound and the releasing mechanism set to operate at a predetermined time, the rod 9 is manually moved toward the left into the position seen 25 in Figs. 1 and 2, the offset 11 of said arm contacting with the key 4, and since the rod 20 is connected with the rod 9, the end of said rod will be located beneath the alarm stopping member 5, and the weight 6 will be raised and the alarm will be in condition 30 to be operated.

Assuming that it is desired to turn off the lights, the circuit is closed by the switch arm 16 being in engagement with the contact 14. When the time for which the alarm has been 35 set is reached, the key rotates, and when it moves into engagement with the end 11 of the rod 9, said rod will be rocked until the offset portion or abutment 10 is in line with the slot 12, whereupon the spring 18 will 40 cause the rod 9 to be moved toward the right, thereby forcing the switch arm 16 out of engagement with the contact 14, thereby opening the circuit and the lights will be extinguished.

Assuming that it is desired to turn on the lights, the fastening device 23 will be actuated, thereby permitting a partial rotation 45 of the switch 13, which is then set in its adjusted position by means of said fastening device, and at this time the normal position 50 of the switch arm 16 will be between the contacts 14 and 15. This adjustment is made depending upon whether it is desired that 55 the operation of the device will close or open the circuit. In the position seen in Fig. 2, the arm 16 is in contact with the point 14 and the circuit is closed until the device operates, then the switch arm 16 is moved from 60 the contact point 14 to a position between the contact points 14 and 15 and the circuit is broken.

If it is desired that the operation of the device closes the circuit the fastening device 65 23 permits the switch 13 to be so rotated that when the arm 16 is engaged by the rod 9,

said arm will be positioned between the contact points 14 and 15, and when the device is operated it will move the arm 16 into engagement with the point 15 and the circuit will be closed and the lights are lighted. 70 This movement of the switch 16 is caused by the rod 9 being moved into contact therewith to throw the switch. Simultaneously, with the turning on or off of the lights, the alarm will be started, as is apparent, thereby 75 awakening the sleeper.

My device is especially adapted for use in stores or show windows, where it is desired that the lights remain on until a certain time, so that by setting the alarm clock at 80 the desired time, the lights will be automatically extinguished when such time is reached.

It will be apparent that as soon as the rod 9 has been moved to the right in the manner 85 herein described, the weight 6 will move downwardly, due to gravity, and the alarm will be shut off, as will be clearly apparent to those skilled in this art.

It will be apparent that in accordance 90 with my present invention, I provide means for automatically actuating a switch, which may be adjusted to turn lights either on or off, and, at the same time, an alarm or signal is sounded.

It will now be apparent that I have devised a novel and useful timed controlling device, which embodies the features of advantage enumerated as desirable in the statement of the invention and the above description, and while I have, in the present instance, shown and described a preferred embodiment thereof which will give in practice satisfactory and reliable results, it is to be understood that the same is susceptible 105 of modification in various particulars without departing from the spirit or scope of the invention or sacrificing any of its advantages.

Having thus described my invention, what 110 I claim as new and desire to secure by Letters Patent, is:—

1. In a device of the character stated, the combination with an alarm clock, having an alarm winding shaft, of a rod movably mounted, means for holding said rod in operative position with an end in position to be actuated by the movement of said shaft, a switch arm in the path of said rod and adapted to be thrown by direct engagement 120 of said rod therewith, and means for moving said rod, when released, to inoperative position to move said switch arm.

2. In a device of the character stated, the combination with an alarm clock, having an 125 alarm winding shaft, of a rod rotatably and slidably supported, means for holding said rod in operative position with an end in position to be actuated by the movement of said shaft, said rod being adapted to be re-

leased when rotated by the movement of said shaft, a switch arm adapted for engagement with said rod, and means for moving said rod to an operative position, when released, and for changing the position of said switch arm.

3. In a device of the character stated, the combination with an alarm clock having an alarm winding shaft of a rod slidably and 10 rotatably mounted in a suitable support, an abutment carried by said rod adapted for engagement with said support in one axial position of said rod, for holding the latter in operative position for engagement 15 with said shaft and to release said rod when rotated by said shaft, a switch arm adapted to be moved by said rod, and means for moving said rod laterally, when released, to change the position of said switch arm.
- 20 4. In a device of the character stated, the combination with an alarm clock, having an alarm winding shaft of a rod slidably and rotatably mounted in a suitable support and having an offset portion adapted for engagement 25 with said support in one axial position of said rod, and adapted to hold the latter in operative position for engagement with said shaft and to be released from engagement with said support when said rod 30 is rotated by said shaft, a switch arm adapted to be moved by said rod, and means for moving said rod laterally, when released, to change the position of said switch arm.

5. In a device of the character stated, the combination with an alarm clock, having an 35 alarm winding shaft, and a weighted alarm stopping member of a rod slidably supported, means for holding said rod in operative position to be engaged with said shaft, a switch arm adapted to be moved by 40 said rod, means for moving said rod, when released, to change the position of said switch arm, and means carried with said arm for normally holding said alarm stopping member in inoperative position and 45 releasing the same when said rod is moved.

6. In a device of the character stated, the combination with an alarm clock, having an alarm winding shaft, and a weighted 50 alarm stopping member of a rod slidably supported, means for holding said rod in operative position to be engaged with said shaft, a switch arm adapted to be moved by said rod, means for moving said rod, when released, to change the position of said 55 switch arm, and an arm movable with said rod and adapted to be positioned beneath said alarm stopping member for holding the same in elevated position, when said rod is in operative position, and to release said 60 member when said rod is moved, whereby said member may move to stop the alarm.
